UNITED STATES PATENT OFFICE.

SETH MOORE, OF SALEM, OHIO.

WAGON-SEAT.

Specification forming part of Letters Patent No. 291,63, dated January 1, 1884.

Application filed September 8, 1883. (No model.)

To all whom it may concern:

Be it known that I, SETH MOORE, of Salem, in the county of Columbiana and State of Ohio, have invented a new and useful Improvement in Wagon-Seats, of which the following is a full, clear, and exact description, reference being had to the annexed drawings, forming part of this specification.

This invention relates to adjustable seats for 10 spring-wagons; and the invention consists of the novel construction hereinafter described and claimed.

In the drawings, Figure 1 is a vertical longitudinal section of a wagon-bed, showing my 15 invention. Fig. 2 is a cross-section on line xx of Fig. 1.

A indicates the sides of the wagon-bed, and B is a metallic strap secured to the upper edge of the sides. The inner surfaces of the sides 20 are recessed at C, just under the straps, in order that the inner edges of the straps may form lips, with which clamps may engage to hold the seat-raiser F to the bed.

The construction above described is recognized as common in this class of inventions. 25 For securing the seat-raiser to the straps B, however, I provide the following construction: The seat-raiser is formed with base-plates G, bent supports H, and braces I, and is adapted

to rest flat upon the straps B. On the inner 30 edges of the plates G are formed lugs J, which overlap the inner edges of the straps and prevent the seat K and raiser F from moving sidewise. The clamps E have inner lips, L, 35 which overlap the inner edges of the straps and engage the under side of the same by means of the grooves C, and have outer lips, M, which overlap the outer edges of the straps. The clamps E have thumb-screws N, which 40 pass through the clamps and plates G, and bear against the upper sides of the straps B when screwed down. The straps B are provided with recesses O, to allow the lips L of the clamps to be passed in and out of engagement with the grooves C.

What I claim is—

The combination, with the wagon-bed having grooves in its sides, of the seat-supporting plates G, having lugs J, the clamps E, having lips L M overlapping the sides of the 50 bed, and screws N, passing through the said clamps and plates and bearing against the sides of the bed, substantially as shown and described.

SETH MOORE.
